OF O 716

Design No. 716

Nathaniel P. Richardson's Design for Franklin Fire Place

Patent 34 July 1853.

Des. 716

Nathaniel P. Richardson, of Portland, Me.
Letters Patent No. 716 Dated July 31st 1855.

The schedule referred to in these Letters Patent and making part of the same
To all Persons to whom these Presents shall come:

Be it known that I,
Nathaniel P. Richardson, of Portland, in the County of Cumberland, and State of Maine, have invented or produced
a new and ornamental design for a Franklin Fire place
or Stove, and I do hereby declare that the same is fully
represented in the accompanying drawings, of which

Figures 1, 2, and 3, are respectively top, front, and
end views of the same.

Figure 4, is a front elevation of its bower.

Figure 5, is a vertical section of its end plate and
door.

Figure 6, is a transverse section of its hearth plate,
the same being taken through the middle of it.

Figure 7, is a vertical section of the front plate

and part of the top plate.

Figure 8, is a transverse section of the top plate.

Figure 9, is a section through the blower.

In these drawings, or in such of them as the same is shown A, A, A, denote the legs of the stove; B, the hearth plate; C, the grate or feeder; D, the front plate; E, the end plate; F, the top plate; G, the blower; H, the end door.

The ornamental character of each of these members of the stove is distinctly set forth by the drawings and so as to enable any pattern maker or person skilled in the art of designing ornamental stoves to readily comprehend and execute the same. The front plate is pierced with an arched opening for the introduction of fuel into the interior of the stove as well as for the radiation of heat therefrom.

What I claim is the ornamental design of the stove as represented in the drawings, and particularly I claim that of each of the members, herein before mentioned.

In testimony whereof I have hereunto set my signature this fifth day of July AD, 1855.
